UNITED STATES PATENT OFFICE

GEORGE MONRO HURST, OF CHIPAWA, ONTARIO, CANADA

MUSICAL MODULATOR

Application filed April 2, 1931. Serial No. 527,138.

My invention relates to improvements in musical modulators, and the object of the invention is to devise a device for teaching the theory of music such as major and minor scale, modulation, transposition, harmony, instrumentation, chords and all intervals pertaining to the study of music, and it consists essentially of the arrangement and construction of parts as hereinafter more particularly explained.

Fig. 1 is a perspective view showing the key board of an organ or similar instrument and that portion of my device extending upwardly therefrom.

Fig. 2 is a rear elevation of the parts shown in Fig. 1.

Fig. 3 is a vertical sectional view on line 3—3 Fig. 2.

Fig. 4 is a perspective view of that portion of my device extending beneath the key board illustrated in Fig. 1.

Fig. 5 is a perspective detail of the mechanism for operating the note indicating stops from a corresponding key of the key board and showing the parts in the normal position.

Fig. 6 is a similar view to Fig. 5 showing the position of the stop when held for sustaining the note.

Figs. 7 to 12 are details showing the faces of the various stops and their colour note indications.

In the drawings like characters of reference indicate corresponding parts in each figure.

1 indicates a key board of an organ or other similar instrument. 2 is a casing provided with side standards 3 and 4 extending upwardly therefrom to form a support for a scale plate 5, such scale plate being supported therebetween over and adjacent to the key board and, therefore, directly in front of the player. The scale plate 5 is provided with vertical parallel slots 6, 7 and 8. The scale plate is divided horizontally by half tone graduations extending at each side of each slot. Adjacent each slot is a vertical row or column of natural note indications indicated at 6^x, 7^x, 8^x and 9^x arranged on the half tone graduations at the usual musical intervals, the columns 6^x, 7^x and 8^x being adjacent the left hand edge of each slot and the col-

umn 9^x being adjacent the right hand edge of the scale plate. The natural note indications start at the bottom with the indicating letter of the note F, the lowest note produced by the keys of the key board and the other letters extending upward in the usual musical intervals. To the left of each vertical column 6^x, 7^x, 8^x and 9^x is a vertical row of orifices 6°, 7°, 8° and 9°, an orifice being in horizontal alignment with each half tone indication.

On the opposite side of the orifices is arranged alternate columns of sharp and flat note indications 10, 11, 12 and 13. That is to say the column 10 shows sharp indications, the column 11 flat indications, the column 12 sharp indications and the column 13 flat indications. As will be readily seen from the drawings these sharp and flat indications are placed in the proper relative positions or intervals to the natural notes as they are arranged on the key board of the instrument. The natural indications are lettered in black and the sharp and flat indications are preferably lettered in red and blue respectively.

14 are a series of stems provided with heads 14^x extending through the orifices 6°. A similar series of stems 15 extending through the orifices 7°, stems 16 extending through the orifices 8° and stems 17 extending through the orifices 9°. It will thus be seen that a horizontal row of stems 14, 15, 16 and 17 are arranged opposite each horizontal row of half tone indications, and the stems of each horizontal row each indicate the same sound produced, thereby indicating the location of the same sound or tone in each scale, one sound both indicating F sharp in the major scale and G flat in the minor scale.

18 is a slidable scale comprising three slide members 19, 20 and 21. As will be seen from referring to Fig. 1 each vertical edge of each member 19, 20 and 21 is provided with a rabbet groove 22 engaging the vertical edges of the slots 6, 7 or 8.

In order to secure the slide members in position a plate 23 is secured to the back of each scale member 19, 20 and 21 so as to overlap the edges of the slots 6, 7 and 8 and form a slideway sliding vertically on the guiding

edges of the slots. The scale members 19, 20 and 21 are connected together by bridging members 24 and 25 each provided with orifices 26 and 27 to permit of the passage of the stems 14, 15, 16 and 17 as the slidable scale is adjusted vertically.

The central member of the slidable scale is provided, on its front face, with a major tonic solfa scale which coacts with the natural note indications on one side and sharp note indications on the other. The right hand slidable scale member is provided with a tonic solfa indication arranged as a melodic minor scale and coacting with the natural indications on one side and the flat and natural indications on the opposite side, the left hand slidable scale being provided with tonic solfa indications arranged for a harmonic scale coacting with the natural and sharp indications on one side and the flat indications on the opposite side.

It will be noted that the faces of the heads of the stems 14, 15, 16 and 17 are provided with variously coloured heads to correspond to the notes they represent and to the colours of the indicating letters if such are coloured, the white being used to indicate a natural note as indicated in Fig. 7 of the drawings, blue to indicate a flat note as illustrated in Fig. 11 and red to indicate a sharp note as illustrated in Fig. 12.

In Fig. 8 I show a combined indication illustrating a sharp and flat note, that is when a sharp note indication of the sharp column is on one side of the stem head and a flat note indication on the opposite side of the stem head. Similarly in Fig. 9 I show a stem head illustrating a sharp note indication on one side and a natural note on the other side, in Fig. 10 a natural note on one side and a flat note on the opposite side. These variously coloured stem heads are arranged as clearly illustrated in Fig. 1 so as to clearly indicate the notes to which they are adjacent.

Between the standards 3 and 4 are journaled transverse rocking rods 28, a rod 28 corresponding to each horizontal row of stops 14, 15, 16 and 17. Each stop of each row is connected to its corresponding rocking rod 28 by means of a spring extension 29 pivotally connected to a curved arm 30 carried by the rod. It will be noted on referring to Fig. 2 that the curved fingers 30 are arranged alternately on opposite sides of the stems 14, 15, 16 or 17. In order to rock the rods 28 I provide each rod with an outwardly extending arm 31.

32 are a series of levers mounted at their inner ends on a cross rod 33 and connected at their free ends by connecting rods or wires 34 to a corresponding arm 31. It will be clearly seen by referring to Fig. 2 that each rod 28 is provided with an arm 31, these arms being arranged diagonally across the back of

the device so that each arm 31 is opposite its corresponding lever 32. Each lever 32 is opposite a corresponding key both natural and sharps of the key board 1. Each key of the key board is provided with a staple 34.

35 is a cross plate pivotally mounted at 36 to the side members of the main casing and provided at its lower edge with an out-turned portion 37 having small orifices 38^x therein, an orifice being located above each key 1^x. 38 is a rod pivotally mounted at its upper end to a corresponding lever 32 adjacent to its supporting rod 33 and provided, at its lower end, with a right angularly turned hook portion 39 adapted to engage the staple 34.

It will, therefore, be seen that when a key is depressed it draws the rod 38 downward so as to swing the outer or free end of the lever 32 also downward and thereby pull open the rod or wire 34 to rock the corresponding rod 28 and, thereby through the arms 30 and their connection to the stems 14, 15, 16, and 17, draw inward a row of such stems which will indicate to the player the note indication in all scales which corresponds to the sound produced by the operated key of the key board.

When it is desired to sustain any note so as to train the ear of the pupil to any particular sound each row of stops, when operated in the above manner, are automatically locked in their depressed position by the following mechanism until released:

Each stem 14, 15, 16 or 17 is provided with a notch 29^x the width of the notch corresponding to the thickness of the scale plate 5. 40 is a slide bar slidably held at its upper and lower ends in guides 41 and 42. Each bar 40 is provided with a row of elongated orifices or slots 43 through which the stems also extend. When the slide bar 40 is in the normal position the lower end of the slot 43 is flush with the lower peripheral portion of the orifices 6°, 7°, 8° or 9° thereby providing a wall thickness which is greater than the width of the notch 29^x and thereby permit the operated stem moving freely in and out.

When it is desired to sustain a note the slide bar 40 is moved vertically downward, the slotted openings 43 permitting this movement so that when a stem is moved inward the notch 29^x thereof will engage with the lower peripheral portion of its opening 6°, 7°, 8° or 9° thereby holding the stop in its 120 inward position.

When it is desired to release the stems after the note has been sustained the required length of time, the slide bar 40 is moved manually in the opposite direction so that the lower end of the slot engages the locked stem so as to lift the notch 29^x thereof out of engagement.

In order to carry the stems back to their normal position each lever 32 is preferably provided with a tension spring 32^x. In order

that the stop bars 40 may be readily operated from the key board I provide a cross bar 44 provided with up-turned ends 45 connected together by a horizontal rod 46 from which

5 extend inward extensions 47 pivotally mounted upon the side walls of the main casing as indicated at 48.

In vertical alignment with each row of stems is a slot 49 through which extends 10 a pin 50, such pin being carried by the slide bar 40. To one of the pins 50 is secured a loop member 51 which is swung upon the cross bar 46. It will thus be seen that the 15 player when playing in any position upon the key board can easily engage the bar 44 with his finger and depress the same so as to carry the slide bar 40 to the locking position to sustain any desired note.

Upon the plate 35 I mount an indicating 20 board 52 which is divided vertically into spaces, each space corresponding to a note of the key board and having inscribed thereon the corresponding stop pin indication hereinbefore described together with the natural, sharp or flat indications corresponding 25 to such stop indication. The board 52 acts as a guide to the student in finding the keys on the key board that operate in conjunction with corresponding movable stops, indicating the letters of the notes that are 30 sounded by the keys being marked over their respective keys together with the coloured indication of the stem.

In order that the slidable scale member 18 35 may be adjusted vertically from a point adjacent the key board I provide upper and lower pulleys 53 and 54 around which extends a cord 55, the ends of the cord being connected to a pin 56 carried by the sliding scale 40 18. The spindle 54^x of the pulley 54 extends through the scale plate 5 and is provided, at its opposite end, with a knob 57 by which the device may be manipulated.

In order that the instrument, in the case of 45 a wind instrument such as an organ, may be thrown in and out of operation by the teacher when standing by the device I provide the following mechanism.

58 and 59 are the operating bellows of the 50 organ provided with arms 60 and 61. 62 and 63 are links provided with slots 62^x and 63^x through which the arms 61 and 62 extend freely. 64 is a crank shaft provided with crank arms 65 and 66 which are oppositely set when connected to the links 62 and 63 as indicated. The crank shaft 64 is provided with a pulley 67 connected by a belt 68 to a pulley 69 mounted on the shaft 70 of the operating motor 71. 72 is a contact plate secured to the main casing in a stationary position and 73 is a contact arm pivotally mounted at 74 upon the casing. 75 is a treadle bar pivoted on the rod 76 and 77 is a spring held link pivotally connected at its lower end 78 65 to the treadle 75 and adjacent its upper end

to the movable contact 73. 79 and 80 are the circuit wires leading respectively from the contacts 72 and 73 to the terminals of the motor 71.

It will thus be seen that when the treadle 75 is depressed the contacts 72 and 73 will be closed thereby closing the motor circuit and operate the bellows through the crank shaft 74.

When it is desired to operate the keys 1^x of the key board independently of my device all it is necessary to do is to release the hook 81 from the pin 82 and then swing the plate 35 rearwardly upon its pivot 36 thereby carrying the hooked ends 39 of the rods 38 out of the staples 34. Whenever desired the plate 35 may be swung inward so as to carry the hooked ends into re-engagement with the staples thereby reconnecting the device to the keys of the key board.

It will thus be seen that by the use of my device the study of music is simplified so that all the scales may be readily taught and the corresponding notes of the scales readily determined, and by this means the study of music will be stimulated and will bring hand played music into the home enabling the teaching of children in large groups in schools and colleges so that they will have a thorough knowledge of the construction of music before taking up the study of any private instrument and thereby ensuring a faster progress and clearer conception of the possibilities of their instrument.

What I claim as my invention is:

1. In a musical modulator, the combination with the keys of the key board, of a scale plate divided vertically by horizontal lines, of half tone graduations corresponding in number to the number of keys of the key board, a plurality of note indicators on each line of graduations and also arranged in vertical rows, a column of natural note indications upon the side of each vertical row, a column of sharp note indications on the other side of certain of said vertical rows, columns of flat note indications on the other side of the other of said rows, both sharps and flats being arranged in conjunction with the natural note indications to correspond with the note arrangement of the key board, a vertical slid- 105 able member carrying vertically arranged tonic solfa indications located between the vertical rows of note indications, and means for operating simultaneously each horizontal row of indicators from the corresponding keys of the key board.

2. In a musical modulator, the combination with the keys of the key board, a scale plate indicating a plurality of scales and a movable indicator for each scale operating in unison by each key and coloured in contrasting colours to represent the natural, sharp and flat indications of the scale plate, of a chart board extending over the back portion of the key 110 115 120 125 130

board and divided to provide a space over each key having thereon the colour indication of the corresponding indicator together with the corresponding note indications of the scale plate.

3. In a musical modulator, the combination with the keys of the key board, a scale plate indicating a plurality of parallel scales, a movable indicator for each scale and corresponding to each key of the key board and coloured in contrasting colours to represent the natural, flat and sharp indications of the scale plate, means detachably connected to each key for operating a corresponding set of such indicators, a plate pivoted at its upper edge and extending over the back of the key board longitudinally thereof and detachably secured at its lower edge, and means operated by the swinging of the pivoted plate for making and breaking the connection between the keys and the operating mechanism of the indicators.

4. In a musical modulator, the combination with the keys of the key board, a scale plate indicating a plurality of parallel scales, a movable indicator for each scale and corresponding to each key of the key board and coloured in contrasting colours to represent the natural, flat and sharp indications of the scale plate, means detachably connected to each key for operating a corresponding set of such indicators, a plate pivoted at its upper edge and extending over the back of the key board longitudinally thereof and detachably secured at its lower edge, and having a perforated flange extending rearward at right angles to such lower edge, a staple carried by the rear portion of each key, a rod extending through each plate perforation over each key and having a hooked end engaging the staple of the corresponding key, and means operated by the longitudinal movement of any one of said rods when a key is depressed for operating the set of movable indicators of the scale plate corresponding to such key.

5. In a musical modulator, the combination with the keys of the key board, a scale plate indicating a plurality of parallel scales, a movable indicator for each scale, means for operatively connecting an indicator of each scale to each corresponding key, means for operating such connecting means by the depression of such key to move said indicators to the indicating position, and means for releasably locking the depressed key and indicators in the indicating position to sustain the tone and the indication thereof.

6. In a musical modulator, the combination with the keys of the key board, a scale plate indicating a plurality of parallel scales, a movable indicator for each scale, means for operatively connecting an indicator of each scale to each corresponding key, means for operating such connecting means by the depression of such key to move said indicators

to the indicating position, means for releasably locking the depressed key and indicators in the indicating position to sustain the tone and the indication thereof, and means extending longitudinally of and adjacent to the key board for operating said locking means.

7. In a musical modulator, the combination with the keys of the key board, a scale plate indicating a plurality of scales and a movable indicator for each scale operated in horizontal sets by each key, a rock shaft paralleling each set, an arm connecting each indicator of each set to the corresponding rock shaft, and connecting means between each rock shaft and corresponding key to rock the shaft by the depression of such key.
